UNITED STATES PATENT OFFICE.

FRANK P. GILLESPIE, OF ERIE, PENNSYLVANIA, ASSIGNOR OF ONE-HALF
TO JOS. I. TOWN, OF SAME PLACE.

DESIGN FOR A SHELL FOR GAS-FUEL BURNERS.

SPECIFICATION forming part of Design No. 28,597, dated May 10, 1898.

Application filed April 1, 1897. Serial No. 630,302. Term of patent 7 years.

To all whom it may concern:

Be it known that I, FRANK P. GILLESPIE, a citizen of the United States, residing in the city of Erie, in the county of Erie and State 5 of Pennsylvania, have invented and produced a new and original Design for a Shell for a Gas-Fuel Burner; and I do hereby declare the following to be a full, clear, and exact description of the invention, such as will enable 10 others skilled in the art to which it appertains to make and use the same, reference being had to the accompanying drawing, and to the letters of reference marked thereon, forming part of this specification.

15 The figure is a perspective view of my new design.

As shown in the drawing, the leading features of my design consist of a shell for a gas-fuel burner which is rectangular in its 20 general shape and the top thereof flat, with transverse slots therein and having a hollow square projection on one end thereof gradually increasing in size to the outer end thereof.

In the drawing, A is a rectangular shell, 25 the vertical depth of which is about one-sixth of the length of the side A' of the shell A,

and in the top B of the shell there are transverse slots b. On the end A² of the shell A there is a projection C, and on the opposite end A³ of the shell A there is a hollow rectangular projection D, the width of which at its junction with the shell is about twice the depth thereof, which depth is substantially that of the depth of the shell A. From the point of junction of the projection D with 30 the shell A to the outer end thereof the width of the projection D gradually increases to the open end D' thereof, and at the sides of the open end D' of this projection there are ears d d.

Having thus described my invention, what I claim as new, and desire to secure by Letters Patent of the United States, is—

The design for a shell for a gas-fuel burner, substantially as herein shown and described. 45

In testimony whereof I affix my signature in presence of two witnesses.

FRANK P. GILLESPIE.
